EDIBLE SERVING SPOON

James Gordon, 3625 N. Halsted St., Chicago, Ill.

Filed Aug. 20, 1962, Ser. No. 71,383

Term of patent 14 years

(Cl. D8—1)

FIG. 1 is a front perspective view of an edible serving spoon, showing my new design;

FIG. 2 is a rear elevational view thereof;

FIG. 3 is a side elevational view of FIG. 2; and

FIG. 4 is a cross sectional view taken on a plane passing through the line 4—4 in FIG. 2 and looking in the direction of the arrows.

I claim:

The ornamental design for an edible serving spoon, as shown.
